BALANCED NECKTIE CONSTRUCTION

Max Kleinmann, New York, N. Y., assignor to
Exactrol Corporation, a corporation of New
York

Application May 5, 1945, Serial No. 592,140

4 Claims. (Cl. 2—146)

1

This invention relates generally to neckties and more particularly to a new and useful balanced necktie construction.

Neckties as heretofore manufactured have been subject among others, to two disadvantages. The first of these is that when the tie is tied about the collar of the wearer insufficient friction exists within the knot so that the necktie during diurnal wear slips and the knot becomes no longer centered in the apex of the forward vertical or angular edges of the collar. This condition is particularly increased where the casing of the necktie is composed of a material having a relatively low coefficient of friction, as for example, satin. Another important disadvantage of necktie constructions lies in the fact that owing to the asymmetrical characteristics of the knot, the smaller wing of the four-in-hand type necktie winds or twists and becomes laterally displaced. When this occurs the tension of the various tie parts within the knot area in seeking an equilibrium, shifts. These frequently result in a distorted arrangement not only of the smaller wing, but of the larger wing as well. This unkempt appearance of the necktie is highly disadvantageous.

It is therefore among the objects of the present invention to provide necktie constructions wherein the above-described disadvantages are overcome with a minimum of care in the donning and tying of the necktie.

In accordance with the present invention, the structure of the necktie is such that even when tied with relatively little skill a balanced knot results within which the wings of the tie are uniformly and symmetrically interleaved. This arrangement of the parts in the knotted tie not only prevents undesired twisting, but also increases the frictional interengagement of the parts reducing materially any undesired slippage.

Another object herein lies in the provision of neckties having the present construction and mode of operation which by virtue of the simplicity thereof may be manufactured at only a slight increase in cost over neckties devoid of these features. This is so because, among other reasons, substantially no additional casing material is required.

A feature of the invention lies in the fact that the present construction may be introduced into the necktie during the normal manufacturing operations or may be applied to an already finished tie.

In accordance with the invention the normally exposed surfaces of the necktie as worn give no

2

substantial evidence of the improved construction. Certain parts of the tie, substantially concealed when the tie is worn do give evidence thereof however, and may furnish a means of identification to the purchaser that the tie is manufactured in accordance with the present construction.

These objects and other incidental ends and advantages will more fully appear in the progress 10 of this disclosure and be pointed out in the appended claims.

In the drawings in which similar reference characters designate characteristic parts throughout the several views:

15 Figure 1 is an elevational view of a four-in-hand necktie constructed in accordance with the first embodiment of the invention showing the rear surface of the larger wing of the tie and the front surface of the smaller wing of the tie.

20 Figure 2 is an enlarged sectional view as seen from the plane 2—2 on Figure 1.

Figure 3 is an enlarged sectional view as seen from the plane 3—3 on Figure 1.

Figure 4 is a fragmentary rear elevational view 25 of the necktie of Figure 1 as tied in one manner.

Figure 5 is an enlarged fragmentary sectional view, schematic in nature as seen from the plane 5—5 of Figure 4.

Figure 6 is an enlarged fragmentary sectional 30 view, schematic in nature as seen from the plane 6—6 of Figure 4.

Figure 7 is an enlarged fragmentary sectional view, schematic in nature as seen from the plane 7—7 of Figure 4.

35 Figure 8 is a sectional view corresponding to Figure 2, but showing a second embodiment of the invention.

Figure 9 is a sectional view corresponding to 40 Figure 3, but showing the second embodiment of the invention.

In accordance with the invention the necktie 45 may be composed of any suitable fabric in generally tubular form in a well-known manner and may include the relatively large wing 11 and the small wing 12. While shown as without a lining, as will be obvious to those skilled in the art to which the present invention relates, where desired, a suitable lining member (not shown) may be incorporated. Thus the necktie 10 may be formed from a blank of material 13 and the herein described novel stitching may be incorporated in the blank 13 prior to the installation of the row of stitches 14 or as will more fully appear 50 hereinafter said stitches may be placed in the

blank 13 after the tie has been otherwise completely fabricated.

Intermediate the large wing 11 and the small wing 12 is a central or neck encircling portion 15 which is adapted to be enclosed within the collar of the wearer as the tie is worn. The large wing 11 includes a front wall or portion 16 and a rear wall 17; the small wing 12 includes a front wall or portion 18 and a rear wall or portion 19. The front or large wing 11 has diverging side edges 20 and 21 and the rear or small wing 12 has diverging edges 22 and 23. The large wing tip is indicated by reference character 24 and the small wing tip by reference character 25.

Extending from the neck encircling portion 15 into the portion of the large wing 11 within that area within which the knot of the tie when tied will form, are a pair of spaced preformed folds 30 and 31. The convex or rib-like formation of the said folds lie upon the forward surface 32 of the rear wall 17 and the corresponding grooves or furrows 40 and 41 are disposed upon the rear surface 33 of the wall 17. The folds 30 and 31 are retained by rows of stitching 36 and 37.

Extending from the neck encircling portion 15 into the portion of the small wing 12 within that area within which the knot of the tie when tied will form is a centrally disposed fold 35. The convex or riblike formation of said fold lies upon the inner or rear surface 38 of the front wall 18 and the corresponding groove 45 is disposed upon the front surface 39 of the wall 18, being retained by stitches 43.

Since the location of the knot 50, when the tie is tied, will vary depending upon the circumference of the wearer's collar, the type of knot, and the tightness with which it is pulled, it is desirable that the folds 30, 31 and 35 extend along their respective wings a substantial distance, so that even when all of the foregoing factors are considered, said folds will always occur within the knot and extend for a substantial distance therebelow. The extension of the folds below the knot provides for an increase in the effective balanced interengagement of the parts as will more fully hereinafter appear.

The fold 35 preferably extends along the central longitudinal axis of the small wing 12. The folds 30 and 31 are preferably arranged so that each substantially bisects the area of the rear wall 17 lying on respectively opposite sides of the longitudinal central axis of the larger wing 11. This arrangement of folds is such as to correspond substantially to the position of the side edges 22 and 23 of the smaller wing 12 in the position said wing occupies after the tie has been tied.

As will appear, in the operation of the necktie the gripping portions 51 and 52 and, 53 and 54, on the large wing 11 will engage the portions 55 and 56 respectively of the small wing 12, and it is desirable that the edges 20 and 21 abut or lie in close proximity to each other but not that they overlap. To this end I have found that the operation is most satisfactory when the folds 30 and 31 are disposed along lines which, if extended in the direction of the neck encircling portion 15 will intersect the point of intersection of lines extended in the same direction from and along the edges 20 and 21.

When the necktie is tied in a normal manner, the fold 35 causes the portions 55 and 56 to approach each other and extend in the general direction of the larger wing within the knot.

The fold 30 causes the portion 51 to approach the portion 52 at the same time engaging the portion 55 therebetween. The fold 31 causes the portion 53 to approach the portion 54 at the same time engaging the portion 56 therebetween. As tied the parts may take the positions shown in Figures 4 to 7, wherein it will be noted that in the area of the knot the lateral portions 55 and 56 are frictionally engaged between the correspondingly positioned corrugations of the folds or furrows 30 and 31. The pressure of the knot and the large effective area for the frictional interengagement of the parts tends to reduce the tendency of the knot and the involved tied portions to slip. In the area below the knot the folds 30 and 31 cause the edges 20 and 21 adjacent thereto to swing rearwardly, that is to say, in the direction of the smaller wing 12, and said rearwardly positioned edges 20 and 21, together with the portions of the larger wing adjacent thereto, act to prevent lateral shifting of the smaller wing since the outer edges 22 and 23 of said smaller wing become completely or partially enveloped by the portions of the outer wing thereon.

Turning now to the second embodiment of the invention illustrated in Figures 8 and 9 for the purpose of avoiding unnecessary repetition parts corresponding to the first embodiment are given 30 the same reference characters with the addition of the numeral 1 as a prefix.

The second embodiment of the invention differs from the first embodiment principally in the formation of the folds 130, 131 and 135 wherein the stitches securing said folds are omitted. The folds 130, 131 and 135 as shown in Figures 8 and 9 are formed by the action of heat and pressure whereby they are pressed into place.

It may thus be seen that I have provided a 40 novel and useful necktie structure which operates in an improved manner. The constructional features providing for the improved operation are concealed as the tie is worn and an improved appearance in the knotted tie results. By virtue 45 of my balanced construction the tendency of the tie knot to drop down from the apex of the collar lapels is markedly reduced and the tie may be worn for relatively long periods without the rear wing stringing, twisting or shifting about to present an untidy appearance in the vicinity below the knot.

I wish it to be understood that I do not desire to be limited to the exact details of construction shown and described, for obvious modifications 55 will occur to a person skilled in the art.

I claim:

1. In a necktie construction of the four-in-hand type: a large wing; a neck encircling portion; a small wing; said large wing in and below 60 the knot forming area thereof having a pair of spaced folds, the convex portions of said folds being directed toward the front surface of said wing; said small wing in and below the knot forming area thereof having a central fold, longitudinally extending, the convex portion of said fold being directed toward the rear surface of the small wing; said fold of the small wing causing the lateral edges of the small wing to be forwardly moved, said folds of the large wing on 65 the rear surface thereof forming furrows within which the side edges of the small wing are engageable, and said folds in the large wing acting to move the side edges of the large wing rearwardly and toward each other to engage said 70 rear wing.

2. In a necktie construction of the four-in-hand type: a large wing; a neck encircling portion; a small wing; said large wing in and below the knot forming area thereof having a pair of spaced folds, each of said folds being disposed substantially in the middle of the area lying between the central longitudinal axis of the large wing and the nearest side edge of said wing, said folds being located on the rear wall of said large wing and having the convex portions of said folds directed toward the front surface of said wing, said folds when the necktie is tied acting to cause the outer side edges of the large wing of the necktie to be moved rearwardly and to hinder lateral displacement of said small wing.

3. A necktie construction as claimed in claim 2 wherein the folds in the large wing are laterally spaced a distance at least equal to the width of the small wing in and below the knot forming area thereof.

4. In a necktie construction of the four-in-hand type: a large wing; a neck encircling portion; a small wing; said large wing in and below the knot forming area thereof having a pair of spaced folds, each of said folds being disposed substantially in the middle of the area lying

15

10

15

between the central longitudinal axis of the large wing and the nearest side edge of said wing, said folds being located on the rear wall of said large wing and being laterally spaced a distance at least equal to the width of the small wing in and below the knot forming area thereof, said folds having the convex portions of said folds directed toward the front surface of said wing, said folds when the necktie is tied acting to cause the outer side edges of the large wing of the necktie to be moved rearwardly and to hinder lateral displacement of said small wing.
